(57) **CLAIM**

The ornamental design for an intercooler tank as shown and described.

DESCRIPTION

FIG. 1 is a top perspective view of an intercooler tank embodying my new design;

FIG. 2 is a bottom perspective view thereof;

FIG. 3 is a rear elevation view thereof;

FIG. 4 is a front elevation view thereof;

FIG. 5 is a side elevation view thereof;

FIG. 6 is an opposing side elevation view thereof;

FIG. 7 is a top plan view thereof;

FIG. 8 is a bottom plan view thereof; and,

FIG. 9 is a perspective view thereof as installed on an environmental intercooler.

The broken lines in the drawings illustrate portions of the intercooler tank and environmental intercooler that form no part of the claimed design.

1 Claim, 9 Drawing Sheets
